UNITED STATES PATENT OFFICE

EDGAR A. RUSSELL, OF SAPULPA, OKLAHOMA

DESIGN FOR A SANITARY TOOTHBRUSH HOLDER

Application filed May 20, 1930. Serial No. 35,700. Term of patent 14 years.

To all whom it may concern:

Be it known that I, EDGAR A. RUSSELL, a citizen of the United States, residing at Sapulpa, in the county of Creek and State of Oklahoma, have invented a new, original, and ornamental Design for a Sanitary Toothbrush Holder, of which the following is a specification, reference being had to the accompanying drawing, forming part thereof. Figure 1 is a front elevation and Figure 2 is a side or edge view of my design.

I claim:

The ornamental design for a sanitary toothbrush holder, as shown.

EDGAR A. RUSSELL.
